(57) **CLAIM**

The ornamental design for a notched hanger with swivel hook and non-slip sections, as shown and described.

DESCRIPTION

FIG. 1 is a front elevational view of a notched hanger with swivel hook and non-slip sections showing our new design, the rear elevational view being a mirror image;

FIG. 2 is a cross sectional view thereof, taken along lines 2—2 of FIG. 1;

FIG. 3 is a right side elevational view thereof, with the swivel hook rotated approximately 45°;

FIG. 4 is a left side elevational view thereof, with the swivel hook rotated approximately 45°;

FIG. 5 is a top plan view thereof, with the swivel hook rotated approximately 45°; and,

FIG. 6 is a bottom plan view thereof, with the swivel hook rotated approximately 45°.
